W. E. COOK.

METHOD OR ART OF MAKING INSULATED WIRE.

APPLICATION FILED APR. 24, 1917.

1,415,156.

Patented May 9, 1922.

FIG 1

FIG 2

William E. Cook INVENTOR

Frank P. Wetmore
BY
his ATTORNEY.

UNITED STATES PATENT OFFICE.

WILLIAM E. COOK, OF NEW YORK, N. Y., ASSIGNOR, BY MESNE ASSIGNMENTS, TO THE PEERLESS INSULATED WIRE AND CABLE COMPANY, OF NEW YORK, N. Y., A CORPORATION OF DELAWARE.

METHOD OR ART OF MAKING INSULATED WIRE.

1,415,156.

Specification of Letters Patent.

Patented May 9, 1922.

Application filed April 24, 1917. Serial No. 164,307.

To all whom it may concern:

Be it known that I, WILLIAM E. COOK, a subject of the King of the United Kingdom of Great Britain and Ireland, residing at St.

5 George, in the borough of Richmond, city of New York, county of Richmond, and State of New York, have invented certain new and useful Improvements in the Method or Art of Making Insulated Wire, of which the following is a specification, reference being had therein to the accompanying drawings, which form a part thereof.

10 My invention relates to a method or art of making insulated wire, and more particularly to improvements in producing wire having an insulation consisting of an absorbent body saturated or impregnated with asphaltum or other composition for waterproofing, and increasing the resistance of the 20 coating material.

15 In a co-pending application of mine, Serial No. 164,302, I have described a method or art which consists in spirally wrapping a cotton sliver about a wire coated with adhesive, and confining the sliver, in compressed condition, upon the wire by wrapping binding threads or cords about the compacted sliver prior to the saturation or impregnation of the sliver and the binding 25 material, with an asphaltum or other composition. In this method or art, the binding threads or cords are wrapped about the sliver in a spiral, the pitch of which is coincident with that at which the sliver is wrapped 30 about the wire. While I have found that a wire constructed in this manner is highly satisfactory, nevertheless there is a possibility that as the result of the exhaustion of the adhesive bond between the sliver and the 35 wire, or throughout the sliver, the sliver might unwind, and the binding threads or cords, being wound spirally about it at the same pitch, would necessarily unwind with it.

40 By my present invention, I avoid a possibility of this condition arising by spirally winding the binding thread or cord about the cotton sliver at a higher pitch than that at which said sliver is wound and in a reverse direction, thus causing each convolution of said binding thread or cord to cross the lap of two or more succeeding convolutions of said cotton sliver according to the pitch at which the binder is moved, in a manner to not only prevent the sliver and

the thread or cord being simultaneously unwound, but to minimize any tendency of the sliver to begin to unwind while the wire is being handled during its installation.

5 By the method or art of my present invention, the covering braid for the wire is entirely dispensed with, and the covered wire is produced by a substantially simultaneous, or continuous operation.

10 The invention consists primarily in the herein described method or art of making insulated wire consisting of winding a cotton sliver spirally about a conductor wire with the edges thereof overlapping, compacting said sliver upon the wire, spirally winding a strand of flexible absorbent material about 15 and embedding successive convolutions thereof within said sliver while it is compacted; said strand being wound in a direction the reverse of, and at a higher pitch than that in which said sliver is wound, and thereafter 20 saturating or impregnating said sliver and said strand with a viscous composition whereby the insulating property is increased, the completed wire is waterproofed and the fibers of said sliver and said strand are 25 bonded together; and in such other novel steps and practices as are hereinafter set forth and described, and more particularly 30 pointed out in the claims hereto appended.

25 Referring to the drawings,

Fig. 1 is a side elevation of a machine showing the manner of applying the cotton sliver and the binding to a conductor wire; and

35 Fig. 2 illustrates an apparatus used in the step of saturating or impregnating the covering for the wire with asphaltum or other viscous composition.

40 Like letters refer to like parts in both views.

45 In the practice of the method or art of my invention, a continuous strand of a conductor wire *a* is passed through a bath of adhesive material indicated at *b* and has imparted thereto continuous traverse at a substantially uniform speed, being passed over the rollers *c* to a rewinding reel (not shown). During this traverse a continuous strip of cotton sliver *d* is spirally wound about the conductor wire *a*, the edges of succeeding 50 convolutions forming a lap joint so as to secure continuity of this cover and substantially the same thickness thereof throughout.

This sliver is applied by means of a rotating platform *e* adapted to carry a container *f* for the sliver, the wire *a* passing vertically through this platform, axially thereof.

- 5 After the application of the sliver to the wire, the wire with the sliver thereon passes through a compressing horn *g* having rotary movement with the platform *e*. Immediately as the wire and the partially compacted covering therefor, passes from the horn *g*, it passes through a rotating frame *i* having mounted thereon one or more spools containing a flexible strand of absorbent material *j* such as cotton thread, or cord which 10 is continuously rotated so as to wind said thread, or cord spirally about the cotton sliver. This thread or cord is subjected to tensioning stresses in any desired manner, so as to cause it to tightly embrace the cotton 15 sliver and be firmly imbedded therein.

By applying the confining thread or cord immediately following the final compression of the cotton sliver, the desired density of the covering material is secured.

- 20 25 Preferably a plurality of independent parallel strands are used, to permit the use of a fairly wide sliver confined at a number of different points by the thread or cord.

In order to cause the strand of thread or 30 35 cord to be wound spirally upon the compressed or compacted sliver, as desired, the frame *i* is rotated in a direction opposite to that in which the platform *e* is rotated, and at lower speed so as to have the pitch of the thread or cord, greater than that of the sliver. In this manner the number of convolutions of the thread or cord per foot will be less than those of the sliver, and a plurality of convolutions of said thread or cord 40 45 will cross the lap between two or more succeeding convolutions of the said sliver, according to the pitch at which the binding thread or cord is wound.

After the cotton sliver has been applied 45 50 to the wire, and confined in position by the spirally wound strand, or strands of thread or cord, the wire with its covering is passed through a tank *k* containing a mass of viscous, insulating, adhesive and waterproof material, such as the asphaltum composition ordinarily used in making insulating wires. The wire after the setting of this composition is waxed and passed through polishing and finishing irons giving the desired, and 55 final finish therein.

By reason of the application of adhesive to the wire before wrapping the sliver spirally thereupon, this sliver will be firmly bonded to the wire so as to resist displacement by the compression horns even though these horns do not have rotary movement.

While the covered wire is in the asphaltum or other similar bath, the cotton sliver will readily absorb this composition by reason of 60 65 the fact that substantial areas of the cotton

sliver project between the strands of thread or cord, which as heretofore stated, are embedded well within the sliver, the portions of the sliver between said strands forming ducts through which the composition may readily flow to the bottom of the sliver.

The compression of the sliver will mat the fibers thereof, the thread or cord preventing expansion after compression; and the application of the asphaltum or other composition causes the fibers to firmly adhere or set, and at the same time firmly bonds the thread or cord to the sliver.

In the finished product the binding threads or cords will not be perceptible as the cotton sliver will ordinarily lap thereover in a manner to completely conceal same.

Preferably, to permit the operation of the machine used at high speed, I employ a cotton sliver having imbedded therein and bonded thereto, a continuous cotton thread or cord which will serve to supplement the action of the binding threads or cords applied to the exterior of the sliver, in holding the sliver in its compacted condition upon the wire.

In this manner, I am enabled by a substantially simultaneous, or continuous operation to apply both the cotton sliver and the binding thread or cord to the wire thereby gaining the advantage over the present methods of avoiding the necessity for passing the wires successively through a machine for wrapping the sliver about the wire, and a machine for applying the cover thereto.

Having described the invention what I claim as new and desire to have protected by Letters Patent is:—

1. The herein described method or art of making insulated wire consisting in winding a cotton sliver spirally about a conductor wire with the edges thereof overlapping, compacting said sliver upon the wire, winding a strand of flexible, absorbent material spirally about and embedding successive convolutions thereof within said sliver while it is compacted, said strand being wound in a direction the reverse of that at which said sliver is wound, and at a higher pitch with succeeding convolutions thereof spaced apart, whereby said strand will cross the lap between succeeding convolutions of said sliver, and ducts will be formed between succeeding convolutions of said strands to facilitate the penetration of a viscous composition throughout the entire body of said sliver, and thereafter saturating or impregnating said sliver and said strand with a viscous composition whereby the insulating property is increased, the completed wire is waterproofed, and the fibers of said sliver and said strand are bonded together.

2. The herein described method or art of making insulated wire consisting in winding a cotton sliver spirally about a conductor

wire with the edges thereof overlapping, compacting said sliver upon the wire, winding a plurality of strands of flexible, absorbent material spirally about and embedding successive convolutions thereof within said sliver while it is compacted, said strands being laid in parallel planes and being wound about said sliver in a direction the reverse of that at which said sliver is wound, 5 and at a higher pitch than that at which said sliver is wound, with succeeding convolutions thereof spaced apart, whereby said strands will cross the lap between succeeding convolutions of said sliver, and ducts will 10 be formed between succeeding convolutions of said strands to facilitate the penetration of a viscous composition throughout the entire body of said sliver, and thereafter saturating or impregnating said sliver and said 15 strands with a viscous composition whereby the insulating property is increased, the completed wire is waterproofed, and the fibers of said sliver and said strands are bonded together. 20

25 3. The herein described method or art of making insulated wire consisting in winding a cotton sliver spirally about a conductor wire with the edges thereof overlapping, compacting said sliver upon the wire, winding a plurality of strands of flexible, absorbent material spirally about said sliver while it is compacted, said strands being laid in parallel planes and being wound about said sliver in a direction the reverse of that at which said sliver is wound, 30 and at a higher pitch than that at which said sliver is wound, with succeeding convolutions thereof spaced apart, whereby said strands will cross the lap between succeeding convolutions of said sliver, and ducts will be formed between succeeding convolutions of said strands to facilitate the penetration of a viscous composition throughout the entire body of said sliver, tensioning said strands while they are being wound to embed them in the sliver, 35 and thereafter saturating or impregnating said sliver and said strands with a viscous composition whereby the insulating property is increased, the completed wire is waterproofed, and the fibers of said sliver and said strands are bonded together. 40

45 In witness whereof, I hereunto affix my signature in the presence of two subscribing witnesses, this 9th day of April, 1917.
